UNITED STATES PATENT OFFICE.

OSCAR VAN KRIEGSFIELD, OF CHICAGO, ILLINOIS, ASSIGNOR TO CRAWFORD TOOL & MANUFACTURING COMPANY, OF CHICAGO, ILLINOIS, A CORPORATION OF ILLINOIS.

TOY.

1,320,362.

Specification of Letters Patent. Patented Oct. 28, 1919.

Application filed January 2, 1919. Serial No. 269,342.

To all whom it may concern:

Be it known that I, OSCAR VAN KRIEGSFIELD, a citizen of the present Government of Austria, and resident of Chicago, Cook county, and State of Illinois, have invented certain new and useful Improvements in Toys, of which the following is declared to be a full, clear, and exact description.

This invention relates to toys and its principal object is to provide a pleasing toy for affording amusement and instruction for children. Another object is to provide a toy of that type, employing balls, marble or other spherical bodies, which roll down an inclined track with automatic means for returning the ball or marble to the highest point of the track, whereby its progress through the track may be continuous.

The invention consists in the several novel features hereinafter fully set forth and claimed.

The invention is clearly illustrated in the accompanying drawings, in which:

Figure 1 is a plan of a toy embodying a simple form of the present invention; Fig. 2, is a vertical, longitudinal section partly broken out and taken on line 2—2 of Fig. 1; Fig. 3, is a detail vertical section taken on line 3—3 of Fig. 2 and Fig. 4, is a detail, horizontal section taken on line 4—4 of Fig. 2.

Referring to said drawings, the reference character 5, designates supporting legs of a framework, which may comprise wire or rods bent up as shown. To said legs is secured an inclined, spirally arranged trough-like track 6, the ends of which communicate with a vertical conduit, here shown in the form of a tube 7. The upper end 8, of the track is covered by a curved deflector 9, which serves to guide certain balls, (shown at 10) from the tube 7 to the track 6. At the place where the lower end 11, of the track joins with the tube 7, an opening 12, is formed in said tube, whereby the balls 10, may enter the tube from the lower end of the track. In the operation of the toy, the balls 10, roll down the inclined track 6 from top to bottom, enter the tube 7, and are thrown up therethrough, by means, to be presently described, and are discharged back on the upper end of the track by the deflector 9.

Adjacent the tube 7, is a second vertical conduit or tube 13, through which other

balls, marbles or spherical objects are dropped from a magazine 14, to a tilting platform 15, which they fall upon and throw the ball 10, back upon the track. The magazine is in the form of a trough and extends from the upper end of the tube 13, in an upwardly inclined direction. It is soldered or otherwise secured to the tube 13, and also supported by a member 16, of the frame. An end wall 17, closes the lower end of the magazine and arrests the balls 18, which, in the operation of the toy, roll down the magazine and are permitted to escape therefrom, one at a time by mechanism presently to be described. The balls 18 are considerably heavier than the balls 10, in order that the force exerted when falling upon the platform 15, will be sufficient to throw the lighter balls 10, back upon the top of the track.

The side of the magazine 14, adjacent the tube 13, is cut away to leave a gap or opening to the tube 13, whereby the balls may, (when permitted) roll from the magazine and into the tube 13. Said gap is normally closed by a gate 19, pivotally connected with the side wall of the magazine, at 20 and acting to prevent the balls from leaving the magazine and entering the tube. The gate 19, is movable in a vertical direction and is connected to the end 21, of the platform 15, by a rod or link 22. The gate 19, is formed with a notch 23, opposite the tube 13, to leave clearance for a ball to pass by the gate when raised.

The platform 15, is pivotally supported between its ends, on posts or other supports 24, and its ends 20, 21 extend into the interiors of the tubes 7, 13, in position to be struck by the balls falling therethrough. The lower ends of the tubes are cut away as 25, 26, to leave openings for the entrance of the ends of the platform. The tubes 7, 13, and posts 24, are secured to supporting member 27, which is soldered or otherwise fastened to frame members 28, that extend from the legs 5. A receiving chute 29, is detachably connected to the member 27, and receives the balls 18, after they have fallen upon the platform 15. When filled the chute 29, may be detached from the member 27, and lifted up to the magazine where the balls 18, may be discharged into the magazine.

In use, the heavy balls 18, are placed in

the magazine 14, care being taken to see that the gate 19, is closed. All of said balls gravitate toward the lower discharge end of the magazine and the lowermost one 5 stands at the side of the gate 19, in readiness to enter the tube when the gate is raised. A light ball 10, is then placed upon the inclined track 6, and permitted to roll down the same finally entering the tube 7, 10 through the opening 12, and falling upon the end 30, of the platform with sufficient force to lower said end of the platform and raise the other end 21, thereby lifting the rod or link 22, swinging up the gate 19, and 15 releasing the lowermost ball 18, which rolls out through the gap in the side wall of the magazine and enters the upper end of the tube 13, through which it falls and strikes the end 21, of the platform with sufficient 20 force to throw the light ball (which lies lodged upon the end 30 of the platform) up through the tube 7, through the deflector 9 and back upon the upper end of the track, down which it rolls and repeats the operation 25 of releasing the heavy balls. The descent of the heavy ball is so rapid that it depresses the end 21, of the platform thereby closing the gate before the next adjacent ball has rolled out of the gap in the magazine wall. After the heavy ball strikes and depresses the end 21, of the platform it rolls into the chute 29, and when a number have 30 collected in the chute, the latter is lifted to the magazine and the balls allowed to roll from it into the magazine. If desired more 35 than one light ball 10, may be used, each acting to release a heavy ball each time it drops on the end 30, of the platform.

More or less variation of the exact details 40 of construction is possible without departing from the spirit of this invention; I desire, therefore, not to limit myself to the exact form of the construction shown and described, but intend, in the following claims, 45 to point out, all of the invention disclosed herein.

I claim as new and desire to secure by Letters Patent:

1. A toy, comprising an inclined trough-like track for receiving a light ball, a vertical tube communicating with the upper and lower ends of the track, an inclined magazine for heavier balls, a tube extending down from the lower end thereof and open-

ing thereto, a gate controlling the passage 55 from the magazine to the tube, a tilting platform, having end portions extending into the lower ends of said tubes, and a link connecting said gate with said platform.

2. A toy comprising an inclined, spirally arranged trough-like track, for receiving a light ball, a vertical tube communicating with the upper and lower ends of said track, a deflector connecting the upper end of the tube with the track, an inclined magazine 65 for heavier balls, a second vertical tube opening to the lower end of said magazine, a gate between said magazine and the second named tube for controlling the passage of the heavy balls to said second named 70 tube, a tilting platform having end portions extending into the lower ends of the tubes, and a link connecting said gate with the platform.

3. A toy, comprising an inclined, spirally 75 arranged trough-like track, a passageway between the upper and lower ends thereof, said track being adapted to receive a light ball, and automatic impact actuated means for throwing said ball from the lower end 80 of the track to the upper end thereof.

4. A toy, comprising an inclined spirally arranged trough-like track, a passageway between the upper and lower ends thereof, 85 said track being adapted to receive a light ball, and means for throwing said light ball from the lower end of the track to the upper end, comprising a tilting platform, one end of which receives the light ball from the lower end of the track, and a heavier 90 ball guided to fall upon the other end of the platform and thereby depress the same.

5. A toy, comprising an inclined, spirally arranged trough-like track, a passageway 95 between the upper and lower ends thereof, said track being adapted to receive a light ball, and means for throwing said light ball, from the lower end of the track to its upper end, comprising a tilting platform having one end in said passageway below the lower 100 end of the track, a tube into the lower end of which the other end of said platform enters, a magazine for heavier balls and a gate controlled by said platform for releasing the heavier balls from the magazine to the 105 tube.

OSCAR VAN KRIEGSFIELD.
